UNITED STATES PATENT OFFICE

CARL S. KLUMPP, OF BROOKLYN, NEW YORK, AND ROBERT R. POTTER, OF JERSEY CITY, NEW JERSEY

BEARING SURFACE

Continuation of application Serial No. 281,629, filed May 31, 1928. This application filed August 18, 1931. Serial No. 557,796.

This invention relates in general to bearing surfaces for supporting sliding doors and the like.

One of the objects of this invention is the provision of an improved construction in bearing surfaces or tracks for sliding doors and the like.

A still further object of this invention is the provision of means of the above type which is adapted to automatically and continuously present a fresh bearing surface to the hanger rollers which support the door as they move thereover.

A further object of this invention is the provision in apparatus of the above type of a bearing surface which may be manually adjusted to present a new bearing surface from time to time.

A still further object of this invention is the provision of a bearing surface of the above type arranged to be free to rotate and/or move longitudinally, actuated by the normal movement of the door hanger rollers to produce continual change of bearing surface for the rollers.

These and many other objects, as will appear from the following disclosure, are secured by means of this invention.

This invention resides substantially in the combination, construction, arrangement, and relative location of parts, all as will be more fully described in this specification.

This application is a continuation of our copending application Serial No. 281,629, filed May 31, 1928.

Referring to the drawing—

Figure 1 represents a side elevational view of one form of the device;

Fig. 2 is a vertical cross-sectional view taken on the line 2—2 of Fig. 1 looking in the direction of the arrows; and

Fig. 3 is a similar cross-sectional view considerably enlarged showing a method of supporting the bearing surface.

Fig. 4 is a cross-sectional view taken on the line 4—4 of Fig. 1 showing how the rollers may be longitudinally displaced in one form of the invention.

It may first be stated that this invention relates to an improved bearing surface for

any type of tracks or hangers for supporting loads on wheels, ball bearings, roller bearings, and the like, such as rolling car door tracks, elevator door tracks, barn door tracks, and other types of tracks and doors wherever the principles of this invention may be applicable.

In the present form of supports for sliding doors as used on street, elevated, subway, railway cars, and the like, a track forming part of or attached to the car structure extends longitudinally of the door opening and above or below it. The doors are supported therefrom by means of hangers or bearings on which are rotatably mounted rollers or balls having convex surfaces which ride on the track. It has been found in practice that the jarring and vibration due to movement of the vehicle and/or door causes these rollers to gradually wear a depression in the track so that it is hard to start the doors in their opening movement because the rollers rest in these depressions. By means of this invention a new bearing surface can be provided without disturbing the car or supporting structure by the simple operation of inserting a new track member in the old support.

The principle of this invention involves the idea of substituting or supplementing the track formerly used by means of a bearing surface which may be arranged so as to be free to rotate and/or move longitudinally by the normal movement of the door to produce a continual change of the bearing surface so that if there is any wear at all it will be uniformly distributed over a wide surface.

In some forms of the device this rotational and longitudinal movement of the bearing may be accomplished by the movement of the door and in other cases it may be accomplished manually and means provided for locking the bearing surface in the desired position. With bearing members other than round, the bearing member can be left free to be moved longitudinally by the movement of the door.

One of the important features of this invention resides in the fact that the new bearing surface may be placed in or added to the member forming the old track so that a worn

out track may be used as a support for the new bearing member. It is, of course, to be understood, however, that the principles of this invention may also be applied to new structures.

5 For a better understanding of the invention reference will now be made to the drawing. It may first be pointed out that the disclosure has been given solely for purposes of illustration and not in any limiting sense 10 since the principles of this invention, as will readily appear to those skilled in the art, may have wide application. At 1 is shown a support, which may be a platform of a car for instance, upon which is mounted the vertical supports 2 and 3 for supporting the overhead structure. It will be readily apparent 15 that these supports 2 and 3 may be replaced by various portions of a vehicle forming the framework thereof. Mounted on the support 20 1 are the members 4, 4 supported to provide in effect a guide for the bottom edge of the door. It is also apparent that this guide may be formed directly in the platform or support 1.

The door is represented at 5 and is provided on its bottom edge with a substantially U-shaped metallic member 6 provided with a relatively thin extension 7 adapted to lie in the track formed by the members 4, 4 and guided by them. Attached to the upper ends 30 of the supports and extending parallel to the lower track is an angle iron 8 to which is secured by any suitable means the channel member 10. At one end of the angle iron 8 and channel member 10 is secured the bracket member 9 and at the other end is attached the bracket member 11. It is understood that the channel member 10 represents in general 35 the old track in which the convex curved rollers normally rode so as to support the door for sliding movement.

When the principles of this invention are applied to old constructions the new track which is shown as a rod or tube 12 is smoothly laid in or on the track member 10. Where this invention is applied to a new structure the channel member 10 may, of course, assume any suitable form for supporting the rod 12 according to the principles of this invention. 45 The upper edge of the door is provided with the hangers 14 on which are rotatably mounted the rollers 15 which have concave surfaces so as to ride smoothly on the rod 12. As shown in Fig. 1 the rod 12 is mounted at one end and extends through a hole in the bracket 11. The rod is provided with two lock nuts 13, one on either side of the bracket 11, so that if desired the rod 12 may be locked in any desired position and upon release of the nuts may be moved longitudinally and/or rotationally so as to present any desired surface thereof to the rollers 15.

As was pointed out above, the greatest wear 60 comes at the point where the doors are sup-

ported when they are closed so that by moving the rod 12 a short distance longitudinally and/or rotationally and locking it there a new surface may be presented to the rollers in the position where the door is closed. In the best form of the device it is not necessary to lock the rod 12 but it is in fact better to leave it free, in which case the locking nuts are omitted and the rod is not threaded. In this form the rod 12 may be left of a length 75 to fit between the brackets 9 and 11, or it may be left shorter than the distance between these brackets 9 and 11 but still of sufficient length to insure continuous support of the rollers 15 in all positions of the door 5, in which case the rod 12 is free to move longitudinally in its supporting channel 10 to a limited extent. When the rod 12 is left free it is held in place by the weight of the door 5 bearing upon said rod through the hangers 14 and the rollers 15. The rod is therefore replaceable without disturbing the channel member 10 or its supports 8, and without the necessity of undoing any fastenings.

When the rod 12 is left free but fits closely 85 between the brackets 9 and 11 as above, its longitudinal movement is substantially prevented but it is free to move rotationally. In this case the rollers 15 are not perfectly aligned with the plane of the rod 12 while 90 said rollers are restrained from substantial side movement by the flanges thereon and/or their attachments 14 to the door 5, and thus the movement of the door 5 produces frictional forces at the contacts between the rollers 15 and the rod 12 which have components tangential to the surface of the rod 12, and as rod 12 is not restrained from tangential movement, the net summative tangential 95 component of these forces causes said rod 12 to rotate about its axis.

On the other hand, if the rod 12 is restricted in any manner against rotational movement but is free to move longitudinally in its supporting channel 10 to a considerable extent, then the movement of the door 5 on the rollers 15 produces frictional forces at the contacts of the rollers with the rod 12 which forces move the rod 12 in the direction of door travel.

Thus as rod 12 moves in a rotational direction when it is limited in its longitudinal travel, and as the rod 12 moves in a longitudinal direction when it is limited in rotational travel, it is obvious that if the rod is unlimited both as to longitudinal and rotational travel, it will be moved longitudinally and/or rotationally by the movement of the door. As is apparent from the foregoing disclosure 110 it is intended that the channel member 10 support the track rod 12 so that that rod is sufficiently free that it may be moved longitudinally and/or rotationally by the rollers as they move over it. It is not necessary therefore that the rod 12 be supported completely 115 120 125 130

throughout its length but only supported sufficiently so that it is free in the above sense. It will be apparent therefore, that the rod is supported substantially throughout its length within the purpose of this invention so long as it is supported sufficiently so that it will be moved longitudinally and/or rotationally as the rollers move thereover whether or not the rollers are longitudinally displaced.

It is pointed out here that it is not necessary, however, to set the rollers out of alignment since it is found that the normal motion of the door effects sufficient movement of the rod both longitudinally and rotationally without positively placing the rollers out of alignment.

It will be at once apparent that we have provided an exceedingly simple and efficient device by means of which the track on which sliding doors are supported may be made to continually present fresh surfaces so that wear upon it will be distributed over a greater area, thus materially lengthening the useful life of the bearing surface member and providing that when wearing surface renewals do become necessary, such renewals may be made by renewal of a light wearing surface rod or member only, in contrast with the heretofore common practice of renewing major portions of or the entire track.

The principles of this invention are not restricted to a track member which is round since we have found that it may be applied to track members having various cross-sectional shapes, such as oval or polygonal, as for instance rectangular and triangular. Where the polygonal shapes are used the rollers will, of course, be modified so as to have suitable surfaces to correctly contact with the track member. In any form of the device, except that using the circular bearing member, no rotational movement will be effected by the movement of the door. Longitudinal movement of the bearing member by manual means may be effected and the bearing member then locked in the desired position. The bearing member is of course not locked against movement when it is intended to have the member move longitudinally by the movement of the door.

Also another form of the device contemplates a track member substantially square in cross-section but having each surface of the rod concave so that a roller having convex surfaces may be used. In this case the track member may be rotated and moved longitudinally by manual means and locked in place or left free. In this case the track member may be moved longitudinally by the movement of the door, or longitudinal and/or rotational movement of the track member may be effected by manual means and the bearing member then locked in the desired position, or it may be left free to move longitudinally.

Furthermore, the principles of this invention may be applied to hangers having one or more wheels whether used in straight line formation or whether mounted parallel to each other and used in connection with many of the well known devices of cage, truck or buggy constructions now used for supporting doors.

It will be at once apparent that many changes in the details of construction and relative arrangement of parts will readily occur to those skilled in this art without departing from the principles of this invention and we do not, therefore, desire to be limited to the exact features of construction shown, but rather to the scope of this invention as it has been defined in the appended claims.

What we seek to secure by United States Letters Patent is:

1. In an apparatus of the type described, the combination with a movable door having hangers thereon and rollers rotatably attached to said hangers, of a support for the door comprising a free rod, said rollers being supported slightly out of longitudinal alignment so as to effect continuous movement of said rod, and means for guiding the door at its lower edge.

2. In a device of the type described, the combination with a slideable door having at least two hangers thereon and a roller rotatably supported on each of hangers, said rollers having concave peripheries and being out of longitudinal alignment, of a support and a round track member freely mounted on said support so as to be rotated by the movement of the rollers thereover.

3. The combination comprising a movable door having hangers thereon and rollers supported on said hangers having concave peripheries, of a channel member supported over said door and a round rod freely supported substantially throughout its length in said channel member and arranged to provide a track for said rollers.

4. In an apparatus of the type described, the combination with a movable door having hangers thereon and rollers rotatably attached to said hangers, of a support for the door comprising a free rod, said rollers being supported slightly out of longitudinal alignment so as to effect continuous movement of said rod upon movement of the door.

5. The combination comprising a movable door having hangers thereon and rollers supported on said hangers, of a channel member supported over said door and a round rod freely supported substantially throughout its length in said channel member and arranged to provide a track for said rollers, said rod being moved longitudinally and/or rotationally by the frictional forces between the rollers and the rod due to the movement of the door.

6. The combination comprising a movable

door having hangers thereon and rollers supported on said hangers, of a bearing member supported over said door, a round rod freely supported substantially throughout its length on said bearing member and arranged to provide a track for said rollers, and means for limiting longitudinal movement of the rod, said rod being moved rotationally by the frictional forces between the rollers and the rod due to the movement of the door.

In testimony whereof we have hereunto set our hands on this 17th day of August, A. D. 1931.

15   CARL S. KLUMPP.
                         ROBERT R. POTTER.
